UNITED STATES PATENT OFFICE.

JAMES DEERING, OF SOUTH PARIS, MAINE, AND DANIEL R. SYMONDS, OF PLANO, ILLINOIS.

GRAIN-BINDER.

SPECIFICATION forming part of Letters Patent No. 274,111, dated March 20, 1883.

Application filed August 22, 1878.

To all whom it may concern:

Be it known that we, JAMES DEERING, of South Paris, Maine, and DANIEL R. SYMONDS, of Plano, Illinois, have made certain new and useful Improvements in Grain - Binders, of which the following is a full description, reference being had to the accompanying drawings, in which—

Figure 1 is a top or plan view; Fig. 2, a section on line 1 1 of Fig. 1, showing the relative positions of the binder and harvester; Fig. 3, a section on line 2 2 of Fig. 1, showing the devices for carrying and rotating the bundle and forming the band; Figs. 4, 5, and 6, details 15 showing the devices for closing the carrying-jaws; Figs. 7, 8, 9, and 10, details of the needle or loop former; Figs. 11, 12, 13, and 14, details of the jaws and the serrated half-rings by which the bundle is rotated.

20 This invention relates to that class of automatic grain-binders in which the bundle is bound by a band formed by drawing loops from the interior of the bundle of grain or other material being bound, and interlocking or interweaving such loops one with the other; and it consists in the means for clamping and discharging the bundle, the means for giving the bundle an intermittent rotation on its axis, while it has an orbital movement, and the 25 means for drawing the loops from the bundle and interlooping them, all as hereinafter described, and particularly pointed out in the claims.

Referring by letter to the drawings, the 30 main frame A, elevator-frame B C, cross-bars D, and upper elevator-roller, E, may be of any of the well-known and ordinary forms of construction for such parts in that class of harvesters in which the grain is elevated over the 35 main or drive wheel, which wheel is located in any suitable manner between the cross-pieces F G on the main frame, except that the cross-pieces D are extended outward a sufficient distance to form supports for the binding mechanism. The complete machine is to be provided with an elevator, carrier, platform, sickle, 40 divider, and other appliances necessary for a complete harvester; but as such parts may be of any of the well-known forms of construction

and arrangement they are neither shown nor 50 described.

The receiver H is located beneath the upper elevator-roller and is secured in any suitable manner to the elevator-frame, its location being such that the grain will be delivered 55 thereon from the upper elevator-roller. It is curved or bent so as to form or partly form the grain into a bundle of the required shape for binding, and facilitate the reception thereof by the jaws. Its rear or inner edge extends 60 up a sufficient distance to form a backing, and prevent the grain from falling beneath the elevator and interfering with the operation of the machine, and its body is provided with two slots or openings, a, for the passage of the 65 jaws N N to take the bundle.

The shaft I is supported in a fixed manner in suitable bearings, b, located at or near the outer ends of the bars D, and on this shaft is mounted the binding mechanism, so that it 70 can be revolved around the shaft as a center.

The collar or sleeve J is mounted on the shaft I, and revolves thereon, movement being imparted thereto by any suitable driving mechanism. To this collar are firmly secured the circular disks K K', one attached to each end of the collar or sleeve, so that as the sleeve revolves the disks will be given a corresponding movement. Near the outer edges of these 75 disks K K', in suitable bearings formed on the 80 disks, is arranged a rock-shaft, L, and the end of this shaft, which has its bearing in the disk K', extends a little distance beyond the outer face of the disk, for a purpose hereinafter explained. This shaft L has a reciprocating 85 rotary movement in its bearings.

The movable jaws M are made in the form of half-circles, so as to give the bundle a round shape, and are firmly attached to the shaft L in any suitable manner that will cause them 90 to be opened and closed by the rocking movements of the shaft. Their location on the shaft L, as shown, is in close proximity to the disks K K' and in line with the slots a in the receiver. The stationary jaws N are also in the 95 form of half-circles, the curvature corresponding to that of the jaws M, so that when the two jaws are brought together the opening

formed will be a circular one. These jaws N are firmly attached to the inner face of the disks K K', by means of the extension e, and rivets or bolts d, or in any other suitable manner, their position being in the same vertical plane as the jaws M, and their free ends in a line radial from the center of the shaft I, so that when the jaws M are closed their free ends will be in contact with the free ends of the jaws N, and a complete circle or ring will be formed, in which the bundle will be firmly held during the process of forming the band.

The half-rings O correspond in form to the jaws in which they are located, and they are secured in place in the jaws by means of the tongue g on each half-ring, which fits into a corresponding groove, f, formed in each jaw, thus allowing the half-rings to slide freely. In order to prevent these rings from slipping or falling out of place, the straps or clasps e are attached to the face of the jaws, and project over the half-rings, holding them in place without interfering with their sliding movement. These half-rings are inserted at the end of their respective jaws, and then forced around so that their ends will coincide with the ends of the jaws. The inner edges or faces of these half-rings project beyond the inner edge or face of the jaws, and are provided with serrations or teeth h, and their outer edges are notched to form the teeth i, with which the end of the pawl j engages for the purpose of advancing or rotating the half-rings and turn the bundle when clasped by the jaws.

The disk P is permanently attached to the shaft I, adjacent to the disk K', and on this disk P are two flanges, Q R, one of which, Q, is located near the periphery of the disk and extends about one-third of the distance around, as shown in Fig. 5, and the other, R, is located opposite to this flange Q, but at a greater distance from the periphery of the disk, and extends around in about the same proportion, as also shown in Fig. 5. One end, w, of the flange Q is curved outward slightly, and the end of the flange R, at the opposite end, is rounded off to a slight extent, as at w', their form and arrangement being shown in Figs. 5 and 6.

On the projecting end of the shaft I is firmly secured the lever S, having two arms, u v, which stand at nearly right angles to each other, and this lever S is so arranged that the arm u, as the disks K K' revolve, will be brought in contact with the inner face of the flange Q, and the other arm, v, will engage or be brought in contact with the outer face of the flange R.

The disk T is stationary on the shaft I, and is secured thereto in any suitable manner. The periphery of this disk is provided with a cog-segment, y, as shown in Fig. 2, and the remainder of the periphery is provided with a smooth face, x, having a flange which presents a delay-surface extending out beyond the line of the cog-segment y.

The shoe U is mounted upon a suitable jour-

nal or pivot located on the disk K, and is so arranged relative to the disk T that its face will engage with the delay-surface x. A pinion, z, is secured to, or is formed with, this shoe U, and is so arranged relative to the disk T as to engage with the cog-segment y. To the pinion z is attached the cog-wheel V, which is located between said pinion z and the disk K. This wheel V gears with a pinion, W, attached to the projecting end of the crank-shaft X, which shaft has its bearings in the disks K K'. By this arrangement the shaft X will be given a rotary movement.

The construction and location of the several parts or devices T U V W X y z are shown in Figs. 1 and 2.

The rock-shaft Y is mounted in suitable bearings located near the periphery of the disks K K', and to this shaft are firmly secured the arms l m. The rod or shaft Z is attached at its ends in any suitable manner to the disks K K', so that it will be stationary or fixed, and its location is nearer the center of the disks than the rock-shaft Y, its location, as well as that of the rock-shaft Y and crank-shaft X, being shown in Figs. 1 and 3.

The needle A' is formed from a single straight bar, pointed at one end and having in its point a notch or recess, j', which inclines inward and toward the point. Extending back from this notch j' is a slot or recess, in which is pivoted the latch C', the pivot g' being back of the center of the needle, as shown in Figs. 7 and 8. This latch C' is pointed at its forward end, as shown in Figs. 7, 8, and 10. Its point is arranged to be on a line with the forward edge of the notch j', and it is bent or curved near its center to form the shoulders h' h'', so that its forward portion will be on a different plane from the portion back of the shoulders. The needle A' is located in the support B', so that it can have a reciprocating movement, the support being secured to the sleeve J, between the disks K K', in any suitable manner, so as to have a revolution with the disks. As shown, this support is formed from a straight piece, having its ends bent at right angles, which ends are provided with openings suitable to receive the needle and allow it to reciprocate therein.

The bar or link e' is attached by the pivot f' to the rear end of the needle A' and the other end of this link or bar e' is pivoted to the end of the arm d', the other end of which arm is secured to the shaft Z in such a manner that it can turn thereon. Between the free end of this arm d' and the shaft or bar Z is pivoted, at c', one end of the bar or link b', the other end of which is pivoted to the crank a' of the shaft X.

The crank-shaft X, as shown, consists of three portions, each end portion being provided with an arm, the ends of the middle portion being also provided with corresponding arms, so that by connecting the arms together by wrist-pins the sections of the shaft are united

and at the same time the cranks $a' o$ are formed. To the crank o is pivoted one end of the bar or link n , the other end of which is pivoted to the free end of the arm m , the other end of the arm m being secured to the rock-shaft Y . Near each end of the rock-shaft Y is secured an arm, l , both arms being within the space between the disks $K K'$. To the free end of each arm l is pivoted the inner end of the pawl j , so that the rotating rings in both sets of compressing-jaws will be provided with pawls, to give them an advance to the same extent and at the same time. To the disks $K K'$, just in advance of the supports k of the pawls j , are secured studs or pins s , each of which has secured to it a spring-arm or spring, r , the outer end of which is provided with a latch or hook, t , arranged to engage the notches i of the half-rings and prevent any backward movement of the half-rings after they have been advanced by the pawls j .

Any suitable means of driving the disks $K K'$, either from the drive-wheel of the machine or from some other suitable point, may be used; but as the precise method of driving is not essential so long as the disks are rotated, no devices are shown for this purpose.

The cranks $a' o$ are arranged on the shaft X in such relation to each other and to the mechanism for operating the pawls j that when the pawls are actuated to advance the half-rings the needle will be withdrawn a sufficient distance to allow of a partial rotation of the bundle, which rotation is the distance required for the next advance of the needle to withdraw the loop.

In operation the grain is delivered into the receptacle H in any suitable manner, and when a sufficient quantity for the bundle is accumulated the rotation of the disks $K K'$ will have carried the jaws N to a position beneath the grain in the receptacle, with the jaws M open and above such grain, as shown in Figs. 1, 2, and 3. Then, as the disks $K K'$ continue to revolve, the jaws N pass through the openings a in the receptacle. The arm u of the lever S comes in contact with the edge of the flange or rim Q , which brings it in contact with the inner or under face of the flange, thus forcing the jaws M closed with their ends in contact with the ends of the jaws N , the grain being tightly clasped between the two jaws. As the disks continue to rotate the arm u will remain in contact with the face of the flange Q , holding the jaws closed. The disks will carry the jaws and the grain around in the arc of a circle with the shaft I as the center. The band is formed and the bundle bound as follows: As the jaws M are closed by the action of the lever S , the shoe U , which during the process of closing the jaws and grasping the bundle has been in contact with the delay surface or rim x , will have passed from the rim, allowing the pinion z to engage with the cog-segment y , so that the rotation of the disks $K K'$ will drive the pinion, and this pinion,

through the wheel V and pinion W , will cause the crank-shaft X to revolve, and with it the cranks $a' o$. The crank a' , through the connecting bar or link b' , arm d' , and connecting-rod e' , gives a reciprocating movement to the needle A' , the advance of the needle causing its point to enter the bundle. As the point projects the incline or bend h' in the latch C' will strike against the shoulder i' and throw the point of the latch below the notch j' in the point of the needle, as shown in Fig. 8, in which position it will remain during the forward movement or thrust of the needle. Upon the return movement of the needle a loop of straw which has been caught in the notch j' will be drawn from the bundle and will remain in the notch until the next succeeding advance or thrust of the needle. The latch C' on the return movement of the needle A' will be thrown out into the position shown in Fig. 7, by the bend or incline h'' striking against the shoulder i'' . The latch in this position retains the loop in the notch j until the needle is advanced to seize another loop. As the needle is again advanced the latch C' is thrown down at its point, as before described, allowing the first loop withdrawn and held in the notch j' to escape from the notch. Then the second loop is drawn from the bundle in the manner before described, the depression of the latch at the same time allowing the first loop to slip out of the notch of the needle and pass over the one just caught and held in the notch j' , thus interweaving the loops so as to form a continuous band. The movements continue until the entire circumference of the bundle has been passed over, and the loops withdrawn and interlocked will form a woven band of straw or other material taken from the interior of the bundle, thus binding the bundle securely with its own material. The bundle is turned at each thrust of the needle the distance required for the formation of each loop by the action of the pawls j on the serrated half-rings O , said pawls being operated by means of the crank o and the connecting devices, the several parts being so timed as to operate in unison and at the proper time. The pawls j are held in engagement with the teeth i and the periphery of the half-rings O by the spring p , the free end of which operates against the pawl, while its other end is secured to a stud or pin, q , on the inner face of the disks $K K'$. The arms l , by which these pawls are advanced, are attached at their inner ends to the rock-shaft Y at the proper point to bring them in line with the pawls, so as to advance and retract the pawls as the shaft Y is rocked forward or back by the crank o , connecting-rod n , and crank-arm m , which arm is located on the shaft Y , between the arms l , at a point where it will not interfere with the operations of the needle and its devices or the other devices composing the mechanism. When the bundle has been rotated, so that its entire circumference has been acted

on by the needle, the pinion z passes from the cog-segment y , and the shoe U engages with the delay-surface x , which will prevent movement of the needle and the half-rings. At the same time the arm v of the lever S engages the flange R , throwing the lever back, and with it the jaws M , thus opening the jaws and allowing the bundle to be discharged. The parts will remain in this position until the jaws N are in position to lift the next bundle from the receiver, when the jaws M are again closed, and the operation of the needle and the serrated half-rings commences anew.

What we claim as new, and desire to secure by Letters Patent, is as follows:

1. The combination, in a grain-binder, of the rotary disks, with the jaws N rigid thereon and formed in half-rings, the movable half-circular jaws M , pivotally connected with said disks, and adapted to form with the jaws N , when closed, a complete circle, the receptacle from which the bundle is raised by the jaws that are rigid upon the disks, and a mechanism for binding the bundle with the material of which it is composed, substantially as described.

2. The combination, in a grain-binder, of a receptacle for receiving the bundle to be bound, two pairs of revolving jaws, arranged to take the bundle from the said receptacle and to compress the bundle, a mechanism for closing the jaws upon the unbound bundle and for opening them to discharge the bundle when bound, mechanism for turning the bundle within the jaws during the act of binding, and mechanism for binding the bundle with the material composing it, substantially as described.

3. The stationary disk P , provided with rims or flanges $Q R$, and the lever S , in combination with the shaft L , jaws M and N , and the disks $K K'$, substantially as and for the purpose specified.

4. The receptacle H , provided with the slots a , in combination with the stationary jaws N , disks $K K'$, jaws M , shaft L , lever S , and disk P , provided with flanges $Q R$, substantially as and for the purpose specified.

5. The combination, in a grain-binder in which the bundle is bound with the material composing it, of the rotary disks $K K'$, with the semicircular jaws $M N$, the half-rings O , provided upon one edge with teeth h , for engaging the bundle, and upon the opposite edges with notches i , and the vibratory pawls engaging said notches i , whereby the bundle will be turned within the jaws as the latter are carried round by the disks, substantially as described.

6. The jaws $M N$, provided with the slots or grooves j , in combination with the serrated half-rings O , provided with the flanges g , and straps or clasps e , for retaining the half-rings in the jaws and permitting their free revolution, substantially as specified.

7. The jaws $M N$, in combination with the

serrated half-rings O , provided with the notches i , the pawls j , and devices for advancing and retracting the pawls, substantially as and for the purpose specified.

8. The jaws $M N$ and serrated half-rings O , located on the jaws and provided with notches i , in combination with the pawls j , arms l , shaft Y , and devices for rocking the shaft, substantially as and for the purposes specified.

9. The jaws $M N$ and serrated half-rings O , located on the jaws and provided with the notches i , in combination with the pawls j , arms l , shaft Y , arm m , link n , and crank o , substantially as and for the purposes specified.

10. The jaws $M N$ and serrated half-rings O , located on the jaws and provided with notches i , pawls j , and arms l , in combination with the shaft Y , arm m , link n , crank o , shaft X , and suitable devices for revolving the shaft X , substantially as and for the purpose specified.

11. The rotating disks $K K'$ and stationary disk T , provided with the cog-segment y , in combination with the pinion z , gear-wheel V , pinion W , and crank-shaft X , substantially as and for the purpose specified.

12. The crank-shaft X , provided with cranks $a' o$, in combination with the mechanism for rotating the bundle and the mechanism for operating the looping-needle, and intermediate operating devices, whereby the bundle-rotating devices and the looping-needle are both operated in proper relation to each other, substantially as described.

13. The crank-shaft X , having a crank, a' , in combination with the bar b' , arm d' , link e' , and needle A' , substantially as and for the purpose specified.

14. The jaws $M N$ and serrated half-rings O , in combination with the pawl j and spring r , provided with a catch, t , substantially as and for the purpose specified.

15. The combination, in a grain-binder in which the grain is bound with the material composing the bundle, of the reciprocating needle A' , for engaging the grain to form the loops, the support B' for the needle, arranged upon the rotary collar J , the disks $K K'$, and the bundle-carrying jaws $M N$, carried by said disks, whereby the needle and the bundle will have corresponding orbital movements around the same center of motion, substantially as described.

16. The needle A' , located on the sleeve or collar J , in combination with the disk T , cog-segment y , pinion z , gear-wheel V , pinion W , shaft X , crank a' , bar b' , arm d' , and link e' , substantially as and for the purpose specified.

17. The needle A' , having a reciprocating movement, and supported by a revolving sleeve, in combination with the latch C' and support and guide B' , for opening and closing the latch, substantially as and for the purpose specified.

18. In a grain-binder in which the grain is bound by a chain of loops formed from the material composing the bundle, the latch C' , hav-

ing a bend, $h' h''$, and pivotally located in the body of the needle A', in combination with the needle having a reciprocating movement, and a suitable support having shoulders $i' i''$, substantially as and for the purpose specified.

19. The shaft X, provided with cranks o a', in combination with the needle A', pawl j, serrated half-rings O, and intermediate operating devices for reciprocating the needle and rotating the half-rings simultaneously, substantially as and for the purpose specified.

20. The revolving collar J, the needle A', disks K K', and the jaws M N, in combination with the disk P and devices operated thereby to open and close the jaws, mechanism located between the disks K K' and supported thereby, disk T, and intermediate operating devices for giving the needle a reciprocating move-

ment, substantially as and for the purposes specified.

21. The revolving collar J, disks K K', needle A', jaws M N, serrated half-rings O, crank-shaft X, and devices for operating the needle and half rings from the crank-shaft, in combination with the disk P and mechanism for operating and closing the jaws M N, substantially as and for the purpose specified.
